UNITED STATES PATENT OFFICE.

FREDERICK MAX PORITZ, OF NEW YORK, N. Y., ASSIGNOR TO STAR CHANDELIER COMPANY INC., OF NEW YORK, N. Y., A CORPORATION OF NEW YORK.

DESIGN FOR A CANDLE HOLDER FOR A CHANDELIER.

Application filed May 29, 1923. Serial No. 6,317. Term of patent 3½ years.

To all whom it may concern:

Be it known that I, FREDERICK MAX PORITZ, a citizen of Germany, residing in New York, in the county of New York and State of New York, have invented a new, original, and ornamental Design for a Candle Holder for a Chandelier, of which the following is a specification, reference being had to the accompanying drawing, forming a part thereof.

The figure is a plan view of a chandelier, showing my new design.

I claim:

The ornamental design for a candle holder for chandelier as shown.

FREDERICK MAX PORITZ.
